CONVERTIBLE ROCKING OR ROLLING
AMUSEMENT DEVICE FOR CHILDREN

Wilfred A. Billinghamhurst, Elizabeth, N. J.

Application May 15, 1948, Serial No. 27,318

4 Claims. (Cl. 155—73)

1

This invention relates to a novel amusement device for children; the device being of a character subject to be optionally produced in a small size to serve as a toy adapted to be convertibly arranged to either roll or rock, or in a large size suitable to be ridden by a child and convertible to be so ridden either as a wheeled carrier or as a rocking carrier.

The invention has for an object to provide a novel amusement device comprising a body of any desired selected form or design, said body being provided with a base structure for supporting or mounting the same, and said base structure comprising a rocker frame having traction wheels associated therewith; means being provided for optionally disposing said traction wheels below the said rocker frame, whereby to condition the device for rolling operation, or above said rocker frame, whereby to condition the device for rocking operation.

The invention has for a further object to provide an amusement device of the above stated character, wherein the rocker frame is provided with front and rear wheel axle bearing structures, the same having lower bearing means for supporting the wheel axles so as to dispose the wheels thereof in traction or service positions, and upper bearing means for supporting said wheel axles so as to dispose the wheels thereof in non-traction or out of service positions; manipulatable means being provided for optionally moving the wheel axles and wheels to and holding the same in either of said positions.

Other objects of this invention, not at this time more particularly enumerated, will be understood from the following detailed description of the same.

An illustrative embodiment of the invention is shown in the accompanying drawings, in which:

Fig. 1 is a side elevational view of the amusement device of this invention, as arranged for rolling operation; and Fig. 2 is a similar view of the same, as arranged for rocking operation.

Fig. 3 is a horizontal sectional view taken on line 3—3 in Fig. 1, but drawn on an enlarged scale; Fig. 4 is a longitudinal sectional view, taken on line 4—4 in Fig. 3; and Fig. 5 is a transverse vertical sectional view, taken on line 5—5 in Fig. 4.

Fig. 6 is a horizontal sectional view taken on line 6—6 in Fig. 2, but drawn on an enlarged scale; Fig. 7 is a longitudinal sectional view, taken on line 7—7 in Fig. 6; and Fig. 8 is a transverse vertical sectional view, taken on line 8—8 in Fig. 7.

2

Similar characters of reference are employed in the above described views to indicate corresponding parts.

Referring to the drawings, the novel amusement device according to this invention comprises a body 10 which may be of any suitable form, but which, as illustratively shown, preferably comprises a figure of selected animal form. The body 10 is mounted upon a novel base structure which comprises a pair of laterally spaced, longitudinally extending, parallel arcuate rocker members 11, to the forward and rearward end portions 12 and 13 of which the body 10 is suitably affixed so as to bridge the base structure. The bottom tread surfaces of rocker members 11 are adapted to rest upon the floor or ground in the rocker borne condition of the device.

Extending across and between and affixed to the rocker members 11, respectively adjacent front and rearward portions of the same, are front and rear transverse tie bars 14 and 15. Associated with the ends of the front tie bar 14 are laterally aligned front wheel axle bearing structures disposed in upstanding relation to the respective rocker members. Said bearing structures are formed to provide rearwardly open lower bearing sockets 16 and forwardly open upper bearing sockets 17; a communicating slideway or guideway 18 being provided to extend between said lower and upper bearing sockets.

One embodiment of the forward bearing structures thus characterized is, as illustrated in the drawings, provided by extensions of the forward transverse tie-bar 14 which overlie the rocker members. Said end portions of the tie-bar 14 are formed to provide stop portions 19, angular to the underlying rocker member, and keeper portions 20 which extend rearwardly from said stop portions above and parallel to the underlying rocker member in spaced relation thereto at a distance corresponding to the diameter of a wheel axle to be served by the lower bearing sockets 16 which are defined by these parts. From the free end of each keeper portion 20 extends an upstanding section 21 which terminates at its upper end in a rearwardly projecting loop section 22 by which an upper bearing socket 17 is defined. From said loop section 22 descends a section 23 which extends downwardly to the underlying rocker member; said section 23 being disposed in parallel relation to the section 21, and being spaced therefrom a distance corresponding to the diameter of a wheel axle, thus defining the slideway or guideway 18 which com-

municates with said lower and upper bearing sockets 16 and 17.

In like manner, associated with the ends of the rear transverse tie-bar 15 are similar laterally aligned rear wheel axle bearing structures disposed in upstanding relation to the respective rocker members. These bearing structures are formed to provide forwardly open lower bearing sockets 24 and rearwardly open upper bearing sockets 25, a communicating slideway or guideway 26 being provided to extend between these lower and upper bearing sockets.

The rearward bearing structures, in an illustrative form thereof as shown, are similar to the above described forward bearing structures, and comprise extensions of the rear transverse tie-bar 15 which overlie the rocker members, and which are similarly formed to provide stop projections 27, angular to the underlying rocker member, and keeper portions 28 which extend forwardly from said stop portions above and parallel to the underlying rocker member in spaced relation thereto at a distance corresponding to the diameter of a wheel axle to be served by the lower bearing sockets 24 which are defined by these parts. From the free end of each keeper portion 28 extends an upstanding section 29 which terminates at its upper end in a forwardly projecting loop section 30 by which an upper bearing socket 25 is defined. From said loop section 30 descends a section 31 which extends downwardly to the underlying rocker member; said section 31 being disposed in parallel relation to the section 29, and being spaced therefrom a distance corresponding to the diameter of a wheel axle, thus defining the slideway or guideway which communicates with said lower and upper bearing sockets 24 and 25.

The reference character 32 indicates a front wheel axle, which is arranged to extend transversely across the forward portion of the base structure, so as to be journaled in and between the above described forward bearing structures. Forward traction wheels 33 are mounted upon opposite ends of said front wheel axle. Similarly, the reference character 34 indicates a rear wheel axle, which is arranged to extend transversely across the rearward portion of the base structure, so as to be journaled in and between the above described rearward bearing structures. Rearward traction wheels 35 are mounted upon opposite ends of said rear wheel axle.

The front and rear wheel axles 32 and 34 are interconnected by manipulatable means for controlling the positioning thereof in either the lower or upper bearing sockets of the aforesaid bearing structures, whereby to optionally dispose the traction wheels either in their service position or in their out of service position.

The positioning control for the axles and wheels is provided by a toggle lever system which is connected with the front and rear axles 32 and 34 to extend therebetween.

Said toggle lever system, in a preferred form thereof as shown, comprises forward lever members 36 having their outer end portions pivotally connected with the front axle member 32, respectively at points inwardly of and adjacent to the respective rocker members 11, and rearward lever members 37 having their outer end portions pivotally connected with the rear wheel axle 34, also respectively at points inwardly of and adjacent to the respective rocker members 11. Said lever members 36 are shaped to converge

toward their inner ends, and the lever members 37 are similarly shaped to converge toward their inner ends, whereby inner ends 38 of the former and inner ends 39 of the latter meet for pivotal interconnection by a pivoting bolt 40 or the like, thus forming the central joint of the toggle lever system. Connected between corresponding lever members 36-37 at the respective sides of the toggle lever system are pull springs 41.

When it is desired to dispose the traction wheels 33-35 in traction service position wherein the same are positioned below the plane of the rocker members 11, so as to condition the device for rolling operation, the toggle lever system is 15 downswung so as to extend or expand the same, and thereby exert outward thrust upon the axle members 32 and 34, thus not only to lower the latter but also to carry them respectively into the lower bearing sockets 16 and 24. In thus depressing the toggle lever system, the lever members 36-37 are downswung, across a dead-center horizontal plane, which intersects the axle members 32-34, to a stopped position wherein the tension of the pull springs 41 holds the toggle lever system depressed in position to retain the axle members against displacement from said lower bearing sockets 16 and 24 (see Figs. 1, 3, 4 and 5). The means for stopping the toggle lever system in the aforesaid depressed position may comprise either one or both of the following provisions. A stop plate 42 is affixed to the inner end portions of the lever members 37 so as to bridge therebetween, and thus be engaged by the projecting extremities of the inner end portions 38 of the lever members 36, and/or laterally projecting stop lugs 43 are provided in connection with the lever members 36 and 37, so disposed as to abut the rocker members 11, and thus limit the downswinging movement of the toggle lever system.

When it is desired to dispose the traction wheels 33-35 in non-traction or out of service position wherein the same are positioned above the plane of the rocker members 11, so as to condition the device for rocking operation, the toggle lever system is upswung so as to contract the same; and thereby exert inward thrust upon the axle members 32 and 34, thus not only to raise the latter through the slideways or guideways 18 and 26 of the bearing structures but also to carry them respectively into the upper bearing sockets 17 and 25. In thus raising the toggle lever system, the lever members 36 and 37 are upswung across the aforesaid dead center plane so as to contract the same, and thereby exert inward thrust upon the axle members 32 and 34 so as to retain the same against displacement from the upper bearing sockets 17 and 25 in which they are entered, whereby the axles and their traction wheels are held in non-traction out of service positions (see Figs. 2, 6, 7 and 8). In such raised positions of the lever members 36-37, the pull springs 41 exert inward pull thereupon whereby the axles 32-34 are entered and held in the bearing sockets 17 and 25 against displacement therefrom, thus holding the traction wheels in the desired out of service position which permits the rocker members to support the device for rocking instead of rolling operation.

From the above description it will be understood that the instant invention provides a novel amusement device which may be optionally produced in small size as a toy or in large sizes so as to be rideable by a child, and in either case the

device is easily and quickly convertible for either rolling or rocking operation at will.

Having now described my invention, I claim:

1. In a device of the kind described, a base structure having parallelly spaced longitudinal rocker members, front and rear axles having wheels mounted on their opposite ends, front and rear bearing means for the respective front and rear axles extending upwardly above the bottom tread surfaces of the rocker members and unitary with said rocker members, said front and rear bearing means having substantially vertical guideways terminating in upper and lower bearing sockets projecting substantially horizontally therefrom in communication therewith, the upper bearing sockets being directed inwardly and the lower bearing sockets being directed outwardly, the front axle being vertically slidable through the guideways of the front bearing means between the upper and lower bearing sockets thereof, the rear axle being vertically slidable through the guideways of the rear bearing means between the upper and lower bearing sockets thereof, the upper bearing sockets being spaced from the bottom tread surfaces of the rocker members at an elevated level adapted to dispose the wheels of the front and rear axles above said tread surfaces, whereby to withdraw said wheels to out of service positions when said axles are engaged in said upper bearing sockets, the lower bearing sockets being spaced from the bottom tread surfaces of the rocker members at a level adjacent thereto adapted to dispose the wheels of the front and rear axles for projection below said tread surfaces, whereby to dispose said wheels in service positions when said axles are engaged in said lower bearing sockets, and a manually operable toggle lever system interconnected between the front and rear axles by which said axles may be simultaneously moved to selectively engage and releasably secure the same in either the upper or lower bearing sockets.

2. In a device of the kind described, a base structure having parallelly spaced longitudinal rocker members, front and rear axles having wheels mounted on their opposite ends, front and rear bearing means for the respective front and rear axles extending upwardly above the bottom tread surfaces of the rocker members and unitary with said rocker members, said front and rear bearing means having substantially vertical guideways terminating in upper and lower bearing sockets projecting substantially horizontally therefrom in communication therewith, the upper bearing sockets being directed inwardly and the lower bearing sockets being directed outwardly, the front axle being vertically slidable through the guideways of the front bearing means between the upper and lower bearing sockets thereof, the rear axle being vertically slidable through the guideways of the rear bearing means between the upper and lower bearing sockets thereof, the upper bearing sockets being spaced from the bottom tread surfaces of the rocker members at an elevated level adapted to dispose the wheels of the front and rear axles above said tread surfaces, whereby to withdraw said wheels to out of service positions when said axles are engaged in said upper bearing sockets, the lower bearing sockets being spaced from the bottom tread surfaces of the rocker members at a level adjacent thereto adapted to dispose the wheels of the front and rear axles for projection below said tread surfaces, whereby to dispose said wheels in service positions when said axles are engaged in said

lower bearing sockets, and a manually operable toggle lever system comprising pairs of divergent forward and rearward lever members having their meeting inner end portions pivotally connected by an intermediate joint and their outer ends pivotally coupled respectively with said front and rear axles, swinging movements of said forward and rearward lever members being adapted to carry said intermediate joint up and down across a dead center defined by a horizontal plane which intersects said front and rear axles, pull spring means extending between forward and rearward lever members, and means to limit downward movement of said intermediate joint across said dead center, limited down swinging movement of the said lever members across said dead center being operative to extend the toggle lever system, whereby to move the axles to and hold the same in lower bearing sockets to dispose the wheels for rolling operation of the device, and upswinging movement of the lever members across said dead center being operative to contract the toggle lever system, whereby to move the axles to and hold the same in upper bearing sockets to dispose the wheels above the bottom tread surfaces of the rocker members to permit rocking operation of the device.

3. In a device of the kind described, a base structure having substantially parallel horizontal rocker members with bottom tread surfaces, front and rear axles extending transversely of said base structure above the bottom tread surfaces of said rocker members, wheels provided on said front and rear axles, front and rear bearing means for the respective front and rear axles disposed above the bottom tread surfaces of the rocker members and forming a part of said rocker members, said front and rear bearing means having substantially vertical guideways and upper and lower bearing sockets projecting substantially horizontally from the respective upper and lower ends of said guideways in communication therewith, the said upper bearing sockets being disposed to project inwardly toward each other from the corresponding guideways and said lower bearing sockets being oppositely directed to project outwardly from the guideways toward the front and rear ends of the rocker members, the opposite end portions of the front axle being vertically slidable within the guideways of the front bearing means and adapted for selective engagement within the upper and lower bearing sockets thereof, the opposite end portions of the rear axle being similarly slidable within the guideways of the rear bearing means and adapted for selective engagement within the upper and lower bearing sockets thereof, the upper bearing sockets being spaced from the bottom tread surfaces of the rocker members sufficiently to elevate the wheels of the respective front and rear axles above said bottom tread surfaces in out of service position when said axles are engaged in said upper bearing sockets, the lower bearing sockets being spaced from the bottom tread surfaces of the rocker members at such a distance that the wheels will project below said bottom tread surfaces in service position when the axles of said wheels are engaged in said lower bearing sockets, a manually operable toggle lever system interconnected between the front and rear axles by which said axles may be selectively engaged with the respective upper and lower bearing sockets and secured releasably in such engagement, said toggle lever system comprising pairs of forward and rearward lever members

having their meeting inner ends pivotally interconnected by a central joint and their outer ends pivotally coupled respectively to said front and rear axles, swinging movements of said forward and rearward lever members being adapted to carry said central joint up and down across a dead center position defined by a horizontal plane in which the axes of the front and rear axles are located, pull spring means interconnected between forward and rearward lever members, and means to limit downward movement of the central joint below the dead center position whereby said pull spring means is prevented from withdrawing the axles from the lower bearing sockets.

4. In a device of the kind described as defined in claim 3, the construction and arrangement of the lever members of the toggle lever system

wherein the respective forward and rearward lever members of each pair are divergent laterally from the central joint toward the ends of the respective axles and wherein said central joint is located substantially at the center of the base structure.

WILFRED A. BILLINGHURST.
